UNITED STATES PATENT OFFICE

ANKER L. CHRISTY, OF CHICAGO, ILLINOIS, ASSIGNOR TO GYRO PROCESS COMPANY, OF DETROIT, MICHIGAN, A CORPORATION OF MICHIGAN

TUBULAR OIL HEATER

Application filed February 16, 1929. Serial No. 340,556.

This invention relates to improvements in oil heaters and has to do particularly with heaters of the type employing tubes or pipes through which the oil under treatment is passed and subjected to the influence of elevated temperatures produced by passing heated gases through a furnace setting in which the tubes or pipes are stationarily positioned. The oil in passing through the pipes may be heated sufficiently to vaporize or partially vaporize the same or may be still further heated to effect molecular decomposition thereof.

In heaters of this type improved results have been secured by placing within the tubes longitudinally extending cores, which being of smaller diameter than the internal diameter of the tubes or pipes, serve to provide substantially annular passages between the adjoining walls of the cores and tubes through which the oil or oil vapor under heat treatment is passed. In this manner very efficient heat transfer between the walls of the tubes and the oil undergoing treatment is permitted, since the heat is imparted to the oil by contact with the latter with the heated surfaces of the tubes with which the oil comes into contact. If the cores were omitted there would be a tendency to overheat the oil which comes into contact with the tube surfaces and to detrimentally crack or overheat the same and yet not to secure sufficient heating of the inner body of oil passing through the tubes, particularly when the oil is in the dispersed phase, since a porous or gaseous body is a relatively poor conductor of heat. To avoid this condition, it has been proposed that such tubes shall be of small diameter but in practice this has been found to be objectionable for various mechanical reasons, since the plan involves the employment of a great number of tubes and difficulty is encountered in connecting serially the ends of the various tubes and also to effect the support of the tubes in the furnace setting so as to overcome the tendency thereof to sag or drop under the high internal temperatures of the furnace.

The present invention therefore provides a tubular heating element in which is remov-

ably positioned a plurality of longitudinally extending cores so located that a relatively thin annular passage is provided between the adjoining walls of the cores and heating element through which the oil under treatment is passed, the tubular heating element having or possessing a standard diameter and of sufficient mechanical strength to resist the deleterious action of highly heated furnace gases, the internal cores serving to block out undesirable areas of vapor travel and to provide for efficient contact for heat transfer purposes between the oil vapor and the heated surface of the tubular element, allowing a tubular element of satisfactory strength and durability to be utilized.

It is another object of the invention to arrange the cores within such tubular elements in axially offset or eccentric relationship to the true longitudinal axis of said element. This is done in order that there will be a greater space for the flow of the oil vapors along that side of the tube which receives the greatest heat input. Of course, if the tube receives heat to an equal degree on all sides then the core is located in the true axis of the tube, but this is a rare condition in furnace design, for the reason that the tubes ordinarily occupy what is known as a tube chamber through which the furnace gases sweep or flow in a single direction. Therefore, in order to obtain the maximum benefit and heat transfer it has been found that by placing the cores to one side of the true axes of the tubes improved heat transfer is secured between the furnace gases and the oil vapors under treatment in said tubes.

A further object resides in the provision of means for locking or positively retaining the cores in fixed positions within the tubes, preventing loss of position of the cores by rotation or from other causes.

With these and other objects in view which will appear as the description proceeds, the invention consists in the novel features of construction, combinations of elements and arrangements of parts hereinafter to be fully described and pointed out in the appended claims.

In the accompanying drawings:

Figure 1 is a view in vertical section of an oil converter or heater formed in accordance with the present invention,

5 Figure 2 is an enlarged vertical sectional view taken through one of the tubes of the heater and disclosing the same provided with the internal core formed in accordance with the present invention,

10 Figure 3 is a vertical transverse sectional view taken on the line 3—3 of Figure 2,

Figure 4 is a detail perspective view of one of the cores.

15 Figure 5 is an enlarged vertical sectional view taken through the inlet header,

Figure 6 is a side elevation of one of the leg members for the core,

20 Figure 7 is an enlarged vertical sectional view taken through a tube having a core of a slightly modified form,

Figure 8 is an end elevation thereof, and

25 Figure 9 is an end elevation of one of the cores.

Referring more particularly to the drawings, the numeral 1 designates an oil heater or converter formed in accordance with the present invention. As usual, this heater comprises a setting 2 provided with an internally arranged bridge wall 3 which divides the 30 setting internally into burner and tube chambers 4 and 5 respectively. Supported by the walls of the setting 2 and the bridge wall 3, and arranged within the tube chamber 5, are rows or passes of longitudinally arranged tubes 6 through which the oil under 35 treatment is circulated. The entrance row of the tubes 6 also passes through the burner chamber 4 in order that the entrance portion of the first pass of tubes may be subjected 40 directly to the intense radiant heat developed within the chamber 4. This first pass or row of tubes is indicated by the numeral 6^a, and its entrance portions are connected with a header 7 into which an oil line 8 is led from 45 other suitable apparatus. In the particular heater under consideration the oil flows into the header 7 in a vaporous state and is then distributed uniformly to each of the tubes constituting the first pass 6^a. The entrance 50 ends of the tubes in the pass 6^a are provided with orifice plugs 9. These plugs are formed with carefully diametered axial passages, so disposed that an equal volume of oil will 55 flow into each of the tubes constituting the pass 6^a.

The oil or oil vapor after flowing through the pass 6^a enters a second header 10 arranged at the rear end of the setting 2, and from this latter header the oil vapor passes 60 into the next lower row or bank of tubes 6^b, and after traversing this bank of tubes the oil vapor enters a third header 11 arranged in the bridge wall 3, and then flows through the lower rows of tubes 6^c and passes from 65 these tubes to fractionating or other appara-

tus not shown. In lieu of headers 10 and 11 individual return bends may be provided between tubes of the passes 6^a, 6^b and 6^c, the return bends being preferable in that there was a tendency to eliminate channeling or 70 uneven flow of the oil vapor through the heating elements.

The tubes 6 are of standard construction but may possess a diameter of approximately three inches and of materials which will stand furnace temperatures of from 1500 to 2000° F., particularly when the tubes are used in the construction of an oil converter wherein the oil vapors are heated, while passing through said tubes, to temperatures in 80 excess of 1000° F. I prefer to employ tubes of such relatively large diameter for the reason that they withstand furnace conditions to far better advantage than tubes of much smaller diameter. However, in order to provide for efficient heat transfer, due to the use of these relatively large tubes, the tubes constituting one or more of the passes 6^a, 6^b and 6^c are provided internally with longitudinally aligned cores 12. In the present instance these cores have been shown as positioned in the top rows 6^a and 6^b, the row 6^c serving as a soaking zone through which the oil vapor flows at reduced velocity and wherein cracking reactions are permitted to 90 take place to perhaps a greater extent than in the previous passes. These cores produce substantially annular passages in the tubes in which they are situated for oil vapor travel. The vapor is most effectively heated by coming into contact with the heated surfaces of the inner tube wall. A gas-to-metal contact produces good heat interchange, and therefore the annular passage, which is designated by the numeral 13, is of relatively restricted form to obtain high thermó-transfer. If the cores were omitted the oil vapor passing through the center of the tube would 100 not be apt to attain the same temperature as that portion of the oil vapor contacting with the tube walls, and this condition has resulted in the employment of unnecessarily high furnace temperatures. This results, first, in an unequal circulation of heat, second, in the overheating of that portion of the oil vapor which contacts directly with the tube walls, causing excessive decomposition of that oil vapor and the production of excessive gas and, third, the underheating of the body of oil which does not come into direct 110 contact with the heated surfaces of the tubes. It is known that poor efficiency obtains in the matter of heat transfer between gaseous bodies as compared with heat transfer between a gaseous body and a solid body. Therefore, by the inclusion of the cores 12 within certain or all of the tubes 6, I am 115 enabled to employ tubes of standard mechanical design and strength and yet obtain a 120 125 130

high rate of heat transfer between the furnace gases and the oil undergoing treatment.

As a result of extensive study of heaters of this type, I have learned that greater efficiency can be obtained by arranging the cores within the tubes eccentrically, that is to say, with the longitudinal axes of said tubes offset with respect to corresponding axes of the tubes. This is done in order that 10 passages 13 will possess their greatest area on that side of the tube which receives the greatest heat input. In practice, the tubes are arranged in the tube chamber 5 and it will be observed that the furnace gases travel 15 downwardly through this chamber from the top or ceiling of the setting toward the bottom thereof, where said gases find outlet from the setting through a stack opening 14. Therefore, in the chamber 5 the cores are positioned so that the vapor passages 13 have 20 their portion of greatest area disposed toward the tops of said tubes and, conversely, the portion of less area at the bottoms of said tubes. The cores in the first pass of tubes 6^a, 25 which are disposed in registration with the burner chamber 4 are located in substantially the reverse order to that described above, for the reason that the greatest heat input is from the bottom of that portion of the tube 30 6^a which passes through the chamber 4.

Each of the cores 12 consists of a suitable length of tubing which may be, for example, 12 inches in length and if the internal diameter of the tubular heating element should 35 be 2.64 inches the outside diameter of the core section may be 2.25 inches. This ratio in diameters provides for a vapor passage 13 of desired area. The core sections may be formed from the same materials as the tubular heating elements. To support the cores within the tubular heating elements, each 40 of said core sections is provided, contiguous to its opposite ends, with annular grooves 15, which receive split metallic rings 16. These 45 rings conform substantially to the outside diameter of the core sections, said rings, however, are provided with outwardly struck legs 17, which engage with the inner walls of the tubular heating elements to properly 50 support the core sections in their applied positions.

When the cores are arranged eccentrically within the tube sections it is desirable to provide means for positively retaining the cores 55 in such eccentric positions to control effectively the shape of the vapor passages 13. This end is primarily obtained by locking the core sections against rotation. A convenient method for accomplishing this consists in 60 providing the end core sections with radially movable prongs or pins 18 which are slidably mounted in radial openings 19 formed in the cores. Each of these pins includes a beveled inner end as at 20, and engageable with the 65 beveled end of each pin is a set screw 21 hav-

ing a conical end. This set screw is accessible from the end of the tube, and it will be seen that by rotating the same in a clockwise direction, the pin 18 may be forced outwardly and radially to bite into the inner wall of the tube. This engagement is so positive as to prevent rotation of the cores or loss of position thereof. The set screw construction described, however, is only provided in connection with the core sections located at the 70 ends of the tubes, and the remaining sections are held against rotation by the provision of a horizontally extending finger 22, which is carried by one end of a core section and extends into the interior of the co-operating and aligned core section, there being an opening 23 formed in the wall of said aligning core section to receive the protruding end of the finger 22. This connection is carried out in the remaining core sections situated in the 75 tubes.

In the modified form of construction disclosed in Figures 7, 8 and 9 of the drawings, the core members 24 have welded thereto at its ends short pin sections 25 which serve as 80 legs for the core when the latter is positioned within the tubular heating elements. As the pins or legs 25 are positioned longitudinally of the core 24 it will be seen that they offer a broad bearing surface to the inside of the 85 tubes and thus eliminate the use of and necessity of pointing the radially movable pins 18' for holding the cores in place.

In view of the foregoing it will be seen that the present invention provides an improved oil heater of the tubular type or so-called pipe still variety wherein efficient heat transfer takes place between the oil vapor passing through the tubes and the internal heat developed within the setting of the 100 heater. This is secured mainly by the provision of the removable cores which provides simultaneously for the employment of large diameter tubes and yet provides for effective 105 heat transfer. The core sections may be removed from the tubes to admit of their cleaning from time to time and, furthermore, are constructed for the purpose of obtaining vapor passages in the tube elements of efficient form and location.

What is claimed is:

1. In an oil heater, a tubular heating element through which oil vapor is adapted to be passed, a plurality of longitudinally aligned core sections arranged in said heating element, means for supporting said core sections in spaced relation from the inner wall of the tubular heating element to define a substantially annular vapor passage, and means for retaining the core sections in fixed 120 positions in connection with the tubular heating element.
2. In an oil heater, a tubular heating element, a plurality of core sections arranged within said heating element and spaced from 125

the inner walls of the latter to provide a substantially annular vapor passageway, spacing elements carried by each of said core sections and arranged to engage with the inner walls of the tubular heating element, and means co-operative with said core sections for restraining the latter against axial rotation within the heating element.

3. In an oil heater, a tubular heating element, a plurality of separable core sections arranged longitudinally within said heating element, the outer walls of said core sections being spaced from the inner walls of the heating element, said core sections having the ends thereof provided with circular grooves, and supporting rings positioned within said grooves and provided with radiating leg portions, the latter being adapted to engage with the inner walls of the tubular heating element to effect the support of the core sections therein.

4. In an oil heater, a tubular heating element, a core section positioned within said heating element, said core section consisting of a cylindrical metallic body of substantially uniform diameter throughout the length thereof, means carried by said core section for supporting the latter within said heating element in axial offset relationship to the longitudinal axis of said heating element, and frictional means for positively locking said core section against axial rotation within the heating element.

5. In an oil heater, a tubular heating element, a plurality of separable core sections arranged longitudinally within said heating element, each of said core sections possessing a substantially uniform diameter throughout the length thereof, means for supporting each of said core sections so that the outer walls thereof are spaced from the inner walls of the heating element and with the longitudinal axis of each core section offset with respect to the corresponding axis of the heating element, and means for positively locking said core sections in fixed positions within said heating element.

6. A core section for tubular oil heaters comprising a cylindrical metallic body of substantially uniform diameter throughout the length thereof, said section being provided with circular grooves at its opposite ends, resilient rings arranged to be positioned within said grooves, said rings being provided with integral radially extending legs for effecting the support of said core section, and a radially movable pin carried by one end of said core section.

7. In an oil heater, a tubular heating element, a plurality of longitudinally aligned core sections arranged within said heating element and disposed to one side of the heating element, means for supporting said core sections so that their walls are spaced from the inner walls of the tubular heating ele-

ment, an eccentrically mounted pin projecting from one end of each of said core sections and arranged to be received within openings formed in the complementary ends of registering sections, said pins serving to prevent relative axial rotation between said sections.

8. In an oil heater, a heating tube, a core positioned in said tube and extending longitudinally thereof, the outer walls of the core being spaced from the inner walls of said tube to provide a longitudinally extending annular passageway for high velocity travel of oil vapor, supporting means for maintaining said core in spaced operative relationship with respect to the inner walls of the tube and providing for free unobstructed non-turbulent flow of the oil vapor through said passageway, and means for positively retaining said core within said tube and secure against axial and longitudinal displacement with respect thereto.

In testimony whereof I affix my signature.

ANKER L. CHRISTY.
